UNITED STATES PATENT OFFICE.

WILLIS B. WOODRUFF, OF CADIZ, KENTUCKY.

LUMBER-MEASURER.

No. 926,631.

Specification of Letters Patent.

Patented June 29, 1909.

Application filed August 17, 1908. Serial No. 448,916.

To all whom it may concern:

Be it known that I, WILLIS B. WOODRUFF, a citizen of the United States, residing at Cadiz, in the county of Trigg and State of Kentucky, have invented a new and useful Lumber-Measurer, of which the following is a specification.

This invention relates to lumber measurers and has for its object to provide a comparatively simple and thoroughly efficient device of this character especially designed for use by lumber inspectors and other persons for measuring and registering the number of square feet in a given length of timber.

15 A further object is to provide a lumber measurer having means for determining the number of square feet in different lengths and grades of timber and which shall take the place of the ordinary rule stick and tally books heretofore employed for this purpose.

20 A further object is to provide a lumber measurer including a casing having a plurality of rack bars slidably mounted therein and arranged to engage corresponding gears or pinions carried by a stub shaft, the latter being operatively connected with suitable registering mechanism mounted on the casing so that when the rack bars are withdrawn from said casing, in the act of measuring a plank, the stub shaft will be rotated to effect the operation of the registering mechanism, and thereby register the number of square feet in said plank.

25 A still further object of the invention is generally to improve this class of devices so as to increase their utility, durability and efficiency.

30 Further objects and advantages will appear in the following description, it being understood that various changes in form, proportions and minor details of construction may be resorted to within the scope of the appended claims.

35 In the accompanying drawings forming a part of this specification: Figure 1 is a perspective view of a lumber measurer constructed in accordance with my invention. Fig. 2 is a longitudinal sectional view of the same. Fig. 3 is a transverse sectional view taken on the line 3—3 of Fig. 2. Fig. 4 is a similar view taken on the line 4—4 of Fig. 2. Fig. 5 is a side elevation of the upper portion of the device showing the manner of connecting the registering mechanism with the stub shaft. Fig. 6 is a detail perspective view of

the upper portion of one of the corner rack bars showing the timber engaging finger in position thereon. Fig. 7 is a similar view of the upper portion of one of the intermediate rack bars.

Similar numerals of reference indicate corresponding parts in all of the figures of the drawings.

The improved lumber measurer forming the subject matter of the present invention 35 includes an elongated casing 5 having its upper end open and its lower end mounted for rotation on an operating handle 6. Arranged within the casing is a cylindrical supporting member 7, the lower end of which is 40 closed by a bearing block 8 having a T shaped recess for the reception of the correspondingly shaped head 9 of the handle 6, whereby the cylinder 7 is retained within the casing 5 and at the same time permitted to rotate 45 with the latter.

Rigidly secured to the head 10 of the cylindrical support 7 is a guide member 11 preferably rectangular in cross section and having a series of vertically disposed recesses 12 50 formed therein for the reception of the rack bars 13. The lower ends of the rack bars 13 are provided with cylindrical shanks 14 which extend through correspondingly shaped openings 15 formed in the head 10 55 and are provided with terminal disks or heads 16 normally disposed parallel with the adjacent face of the block 8. Surrounding the shanks 14 of the racks and interposed between the heads 10 and 16 are coiled springs 60 17, which serve to normally and yieldably support the rack bars 13 within the casing. Mounted in suitable brackets 18 at the open end of the casing 5 are a plurality of stub shafts 19 to which are keyed or otherwise 65 rigidly secured a series of spaced gear wheels or pinions 20 of different sizes adapted to engage the teeth on the adjacent racks 13 when the latter are moved into engagement therewith, as best shown in Fig. 2 of the drawings. 70 The apertures 15 are preferably just large enough to permit vertical movement of the racks 13 within the casing 5 without allowing any side play of said racks within said apertures, said racks possessing sufficient resiliency to bend from the perpendicular line above the aperture 15 to a position in engagement with the adjacent pinions, as best 75 shown in Fig. 2 of the drawings. Secured to one end of each stub shaft 19 is a crank arm 80

or eccentric 21 having a link 22 secured thereto and connected through the medium of a system of levers 23 with a registering mechanism 24 of any approved construction, 5 the latter being housed within a suitable casing and adapted to register the number of square feet in any desired length of timber when the racks 13 are withdrawn from the casing.

10 The rack bars, twelve of which are preferably provided, are extended longitudinally beyond the open end of the casing 5 and provided with smooth portions 25 upon which may be printed, stamped or otherwise represented numerals corresponding to the length 15 of the timber capable of being measured by said rack bars, the different lengths of timbers being represented by the numerals 10, 12, 14 and 16, as best shown in Figs. 2 and 5 20 of the drawings. The rack bars on each side of the guide member 11 are similar in construction and provided with similar numerals at their upper ends to indicate the length 25 of the lumber to be measured, the object of having four sets of rack bars being to permit the use of the device on different grades of lumber, a separate register 24 being employed for registering each grade of lumber.

Extending laterally from each side of the 30 casing and mounted for rotation in suitable brackets 26 are anti-friction rollers 27 which travel over the upper surface of the plank or timber when the latter is being measured.

Secured to one of the rack bars 12 on each 35 side of the guide member 11 is a detachable finger 28 adapted to engage one edge of the plank so that when a longitudinal pull is exerted on the handle 6, said rack bar will engage the adjacent pinion 20 and through the 40 medium of the adjacent crank 21 and rod 22 actuate the registering mechanism to register the number of square feet in said plank. One end of each finger 28 is provided with a pointed terminal, while the opposite end 45 thereof is formed with a square socket 29 arranged to engage the smooth portions 25 of the rack bars, there being a set screw 30 piercing the squared portion 29 and adapted to bear against the adjacent rack bar for locking the finger in position on said rack bar.

In determining the number of square feet in any desired length of plank the finger 28 is arranged in contact with one edge of the plank and the handle 6 manipulated so as to 55 bend the adjacent rack bar 13 into engagement with the corresponding gear 20 after which a longitudinal pull is exerted on the handle which causes the teeth on the rack bar to engage the teeth on the pinion and rotate 60 the stub shaft to effect the operation of the registering mechanism, in the manner before described. When it is desired to measure a different length of timber, say for instance, a ten foot plank the clamping screw 30 is 65 loosened and the finger 28 removed and

placed on the rack bar having the numeral 10 stamped on the upper end thereof and the above operation repeated. In order to measure a different grade of timber, the casing 5 is rotated on the handle 6 until the desired 70 bank of rack bars is positioned over the timber or plank to be measured and in which position, said rack bars may be moved into engagement with the adjacent pinions 20 to measure the lumber. After the rack bars 75 have been withdrawn from the casing and the finger 28 released from the adjacent edge of the plank the spring 17 will automatically return said rack bars to inoperative position within the casing, the usual ratchet mechanism being arranged within the casing of each register 24 for preventing backward rotation of the same during the rearward movement of the rack bars.

Attention is here called to the fact that 85 the angular member 11 not only serves to center the rack bars within the casing or housing 5 but also serves to guide said rack bars when the latter are moved to operative and inoperative positions.

The device may be made in different sizes and shapes and provided with any number of banks of rack bars without departing from the spirit of the invention.

Having thus described the invention what 95 is claimed is:—

1. A lumber measurer including a casing, registering mechanism carried by the casing, a shaft operatively connected with the registering mechanism, a pinion secured to the 100 shaft, and a resilient rack bar slidably mounted within the casing and movable laterally into engagement with the pinion for rotating the shaft to actuate the registering mechanism.

2. A lumber measurer including a rotary casing, a plurality of stub shafts each having a series of spaced pinions secured thereto, separate registering mechanism operatively connected with each shaft, and a plurality of 110 banks of rack bars carried by and movable with the casing and adapted to engage the adjacent pinions for actuating the registering mechanism.

3. A lumber measurer including a casing, registering mechanism secured to the casing, a shaft, spaced pinions of different sizes secured to the shaft, a connection between the shaft and registering mechanism, and a bank of rack bars arranged within the casing, said 115 rack bars being resilient and bendable laterally into engagement with the pinions for rotating the shaft to actuate the registering mechanism.

4. A lumber measurer including a rotary casing, registering mechanism carried by the casing, a support mounted for rotation with the casing, a shaft operatively connected with the registering mechanism, a pinion secured to the shaft, and a spring actuated rack

bar slidably mounted in the support and adapted to engage the pinion for rotating the latter to actuate the registering mechanism.

5. A lumber measurer including a casing, registering mechanism secured to the casing, a shaft operatively connected with the registering mechanism, a pinion carried by the shaft, a resilient rack bar slidably mounted within the casing and movable laterally into 10 engagement with the pinion for rotating the latter to actuate the registering mechanism, and a finger secured to one end of the rack bar.

6. A lumber measurer including a casing, 15 registering mechanism secured to the casing, a transverse shaft mounted for rotation at one end of the casing and operatively connected with the registering mechanism, a plurality of spaced pinions secured to the shaft, 20 a support arranged within the casing, a guide member secured to the support and having longitudinally disposed recesses formed therein, resilient rack bars slidably mounted in said recesses and movable laterally into

engagement with the pinions for rotating the latter to actuate the registering mechanism, and springs housed within the support and surrounding the rack bars for normally and yieldably retaining said rack bars within the casing.

7. A lumber measurer including a casing, 25 registering mechanism secured to the casing, a shaft operatively connected with the registering mechanism, a pinion secured to the shaft, a resilient spring actuating rack bar 30 slidably mounted within the casing and adapted to engage and rotate the pinion to actuate the recording mechanism, and a finger secured to one end of the rack, the teeth on said rack bar being normally out of contact 35 with the teeth of the pinion.

In testimony that I claim the foregoing as my own, I have hereto affixed my signature in the presence of two witnesses.

WILLIS B. WOODRUFF.
